DESIGN FOR A DRESS

Benjamin Cooper and Saul S. Bickel,
New York, N. Y.

Application October 9, 1947, Serial No. 141,820

Term of patent 7 years

(Cl. D3—26)

To all whom it may concern:

Be it known that we, Benjamin Cooper and Saul S. Bickel, both citizens of the United States, residing at New York, in the county of New York and State of New York, have invented a new, original, and ornamental Design for a Dress, of which the following is a specification, reference being had to the accompanying drawing, forming a part thereof.

In the drawing:

Fig. 1 is a front elevational view of a dress, showing our new design; and

Fig. 2 is a rear elevational view of the same.

We claim:

The ornamental design for a dress, as shown.

BENJAMIN COOPER.
SAUL S. BICKEL.
